CALVIN L. HUBBARD, OF NEW HAVEN, CONNECTICUT, ASSIGNEE TO THE
NEW HAVEN STEAM-HEATING COMPANY, OF SAME PLACE.

Design No. 4,886, dated May 9, 1871.

DESIGN FOR A SCREEN FOR A STEAM-HEATER.

The Schedule referred to in these Letters Patent and making part of the same.

To all whom it may concern:

Be it known that I, CALVIN L. HUBBARD, of the city and county of New Haven, State of Connecticut, have invented a new Design for Screen for Steam-heaters; and I do hereby declare that the following, when taken in connection with the accompanying photographic illustration, is a full and exact description of the same, and which said illustration constitutes part of this specification and represents a front view of the screen.

This invention relates to a design for screen to cover steam-heating radiators, and consists in the peculiar configuration and ornamentation of the screen, as shown in the accompanying photographic illustration, to which reference is made.

I claim as my invention—

The design for screens, as shown.

Witnesses: CALVIN L. HUBBARD.
